UNITED STATES PATENT OFFICE.

LEWEN R. NELSON, OF PEORIA, ILLINOIS.

LAWN-SPRINKLER.

1,202,208.

Specification of Letters Patent. Patented Oct. 24, 1916.

Application filed June 19, 1913; Serial No. 774,560. Renewed September 5, 1916. Serial No. 118,550.

To all whom it may concern:

Be it known that I, LEWEN R. NELSON, a citizen of the United States, residing at Peoria, in the county of Peoria and State of Illinois, have invented certain new and useful Improvements in Lawn-Sprinklers, of which the following is a specification.

My invention relates to certain new and useful improvements in lawn sprinklers.

10 The purpose of my invention is to provide a sprinkler body adapted to sprinkle an area less than a complete circle, with a view of leaving a clear space at the inlet or rear portion of the sprinkler body that will provide 15 a clear approach for the user.

20 A further object of my invention is to more uniformly sprinkle a given area than would be the case if but one row of discharge openings were provided in the sprinkler body, and to this end I provide the relatively placed partial circles of openings disposed in different arcs, also I obtain a broad base and reduce cost materially.

25 My invention consists in constructing a sprinkler body with a portion preferably partially circular and having substantially vertical walls, and with a substantially straight cross portion connecting and communicating with the circular part, and likewise having substantially vertical walls, thereby gaining strength from very light material and providing a large interior open space surrounded by said walls which will give the body an extended base-support.

30 35 The curved and straight portions of the sprinkler body are designed to be united to form a continuous interior channel as disclosed. In connection with the circular portion of the body, a series of perforations is 40 provided, preferably describing an arc substantially co-extensive therewith, and a series of perforations is also provided within the rear transverse portion, preferably disposed in arc shape, as above indicated. The transverse or rear section of the sprinkler body 45 may be provided with a raised portion in its upper face adjacent the inlet and the perforations may be provided therein so as to cause a discharge forwardly and laterally 50 with relation to the sprinkler body.

55 My invention may be applied to a circular body by arranging the discharge perforations to comprehend only a portion of the circle described by such body, and by arranging another series of perforations rearwardly of the aforesaid perforations, whereby sub-

stantially the same effect may be obtained as in the first mentioned plan.

Referring to the drawings, Figure 1 is a plan view of one form of my invention; Fig. 2 is a sectional view on the line 2—2 of Fig. 1; Fig. 3 is a plan view of another form of my invention, and Fig. 4 is a sectional view on the line 4—4 of Fig. 3.

I am aware of the fact that in the sprinkler art, it is not new to arrange the discharge openings in the sprinkler head in such a manner as to accomplish a discharge in advance of the sprinkler head, leaving the rear portion thereof approachable, as I am the applicant for a patent at the present time upon such a type of sprinkler head, and furthermore, the company with which I am associated, is the owner of the patent to Chas. Ballreich, No. 943,172, dated Dec. 14, 1909, which I believe, contains the first suggestion of this plan, but I find from experience that under certain conditions of use, a sprinkler head constructed in pursuance of the Ballreich patent, if made with a reasonable saving of material, is too small and has not sufficient bearing surface to maintain it in the proper contact with the ground surface, as it is liable to tip through the torsion of the hose. By enlarging the circle, I increase the surface contact of the sprinkler body and reduce the amount of material necessary to be used, by cutting out the central body portion, leaving a large central opening, furthermore, by obstructing the inflow opposite and near to the inlet I am able to get a stronger discharge through openings near the inlet than if the head were entirely open as in Ballreich.

Referring to the drawings, 2 denotes generally the sprinkler head. It is preferably formed of sheet metal, but may be cast, and comprises a substantially arc shaped part 3 and a substantially rectangular portion 4 extending transversely of the sprinkler head and meeting the walls of the arc shaped part 3 to complete a continuous passageway within the shell that produces the sprinkler body. The arc shaped portion of the sprinkler body has the forwardly inclined wall portion 5 extending thereabout, which portion is perforated as at 6 throughout substantially the entire arc, which disposition of the discharge openings effects a discharge at either varying or uniform angles in intersecting planes having substantially a common center. This disposition of the

perforations causes a discharge entirely about the arc shaped portion of the sprinkler head, both in front and at the sides, leaving the rear portion of the sprinkler 5 head approachable.

7 is a semicircular raised portion struck up from the body of the cross section 4 of the sprinkler and I provide perforations as 10 about the said raised portion, arranging the same in arc form, as disclosed, serving through the formation of the raised portion and the arc shaped disposition of the openings, to accomplish a discharge of water in the same direction and comprehending completely 15 the entire arc of the sprinkling head, but effecting a deposit of the water at points intermediate the partial circle described by the arc shaped portion of the sprinkler body and the point of deposit of the discharge 20 from the openings in said arc formed part, thereby accomplishing a more thorough and equal distribution thereof.

I may vary the extent and form of the raised portion 7 to cause it to comprehend 25 a greater or less portion of the transverse part 4 and may similarly increase or diminish the number of discharge openings within said raised portion to suit conditions of use for which the sprinkler head may 30 be designed.

I provide the raised portion 7 for the additional purpose of providing a seat and clearance for the threaded inlet portion 9. It will be noted that in the disclosure made 35 of my structure, the wall portion of the sprinkler body is of substantially uniform height and size, but in practice I am able, because of the enlargement of the sprinkler body as at 7, which takes care of and provides 40 space for the proper placing of the inlet, to reduce the size of the remaining portion of the sprinkler body materially so that it will not need to stand so high from base to top, thus accomplishing a material saving 45 in cost of production and a corresponding lessening of the cost to the user.

In Figs. 3 and 4 I have shown my invention in a somewhat different embodiment from that disclosed in the other figures of the drawing. This modified construction involves the same principle and the same functional sprinkling results are sought to be obtained as in the other figures. In this modified form, 10 refers generally to the sprinkler body. It comprises lower section 11, and upper section 12 joined together in a manner to provide a water passageway 13. The upper, outer edge of the sprinkler body is inclined as at 14 for the same purposes as described in connection with the disclosure in Figs. 1 and 2. Perforations are disposed within the inclined wall portion throughout a portion of the circle described by the sprinkler body so that a discharge may be effected 60 at right angles from the inlet as well as in

front of the same. I provide the raised portion 15 and provide the perforations in arc arrangement for the same purposes as in the structure previously described, the only difference between the two structures being 70 that of form.

Realizing that the principle involved and the results obtained may be reached by other embodiments than those disclosed herein, I do not limit myself to the particular forms shown, but claim all forms that fall legitimately within the principle involved. 75

What I claim is:

1. In a device of the class described, the 80 combination of a flat bottomed casing having a continuous channel therein partly semicircular and partly straight, a hose connection opening into the straight channel, the wall of the convex side of the semi-circular 85 channel comprising an inclined portion facing outwardly and upwardly, a second forwardly curved inclined portion on the wall of the straight channel in rear of the first mentioned inclined portion, and a series 90 of perforations in each of said inclined walls adapted to discharge over a surface in advance of the straight channel.

2. In a device of the class described, the 95 combination of a D-shaped casing comprising an outwardly curved semi-circular channel connected at its ends by a straight channel, a hose connection opening into the straight channel, the wall of the convex side of the semi-circular channel comprising an 100 inclined portion facing upwardly and outwardly, a second forwardly curved portion on the wall of the straight channel in rear of the first mentioned inclined portion and inclined in the same general direction but at 105 a different angle, and a series of perforations in each of said inclined portions adapted to discharge over a surface always in advance of the straight channel.

3. In a device of the class described, the 110 combination of a D-shaped casing comprising an outwardly curved semi-circular channel connected at its ends by a straight channel, a hose connection opening into the straight channel, the wall of the convex side 115 of the semi-circular channel comprising an inclined portion facing upwardly and outwardly, a row of perforations in said wall from end to end through which water is discharged forwardly and laterally over a surface always in advance of the straight channel, a second forwardly curved portion on the top of the straight channel in rear of the first mentioned inclined portion and inclined in the same general direction but 120 at a different angle, and a curved row of perforations in said portion through which water is discharged in a direction to intersect the water issuing from the perforations 125 in the first inclined portion. 130

4. In a device of the class described, the combination of a D-shaped casing comprising an outwardly curved semi-circular channel connected at its ends by a straight channel, a hose coupling opening into the center of the straight channel, the wall of the convex side of the semi-circular channel comprising an inclined portion facing outwardly and upwardly, a second forwardly curved inclined portion on the top of the straight channel in rear of the first mentioned inclined portion and in closer relation to the outlet of the hose coupling than said portion, the second curved wall having the same general direction as the first curved portion but inclined at a slightly different angle, and a series of perforations in each of said inclined portions through which water is discharged over a surface in advance of the straight channel.
5. A sprinkler head comprising a D-shaped body portion including a convexly curved semi-circular channel connected at its ends by a straight channel, a hose coupling opening into the straight passage, a row of perforations in the convex edge of the semi-circular channel inclined to discharge water upwardly, forwardly and laterally only of the sprinkler head, and a second row of perforations in the top of the straight channel curved to a shorter radius than the first row and eccentrically disposed in rear thereof and adapted to discharge water upwardly, forwardly and laterally and intersect the water from the first row.
6. A sprinkler head comprising a D-shaped body portion, including a semi-circular channel connected at its ends by a substantially straight channel, said semi-circular and straight channels being formed each with top wall, substantially vertical side walls and a flat bottom wall attached to the side walls; a hose coupling opening into the straight passage, a row of perforations in the semicircular channel, disposed to discharge water upwardly, forwardly and laterally only.
7. A sprinkler head comprising a D-shaped body portion, including a convexly curved semi-circular channel connected at its ends by a straight channel, said semi-circular and straight channels being formed each with top wall, substantially vertical side walls and a flat bottom wall attached to the side walls; a hose coupling opening into the straight passage, a row of perforations in the convex edge of the semi-circular channel, inclined to discharge water upwardly, forwardly and laterally only of the sprinkler head.
8. In a lawn sprinkler, a body portion comprising a walled arc shaped duct provided with perforations co-extensive with and conforming in arrangement substantially to the shape of said duct, a walled straight duct, its ends communicating with the terminals of said arc shaped duct to constitute a continuous passageway about the body so formed and inclosing a central opening bounded by the walls of said sprinkler body, an inlet and perforations in the upper face of the straight duct arranged in an arc substantially conforming to that of the perforations in the arc shaped duct, the axes of discharge of the perforations of both sets being wholly in advance of a perpendicular plane through the bore of the inlet.
9. In a lawn sprinkler, a body portion comprising a vertical walled arc shaped duct provided with perforations co-extensive with and conforming in arrangement substantially to the shape of said duct, a vertically walled straight duct, its ends communicating with the terminals of said arc shaped duct to constitute a continuous passageway about the body so formed and inclosing a central opening bounded by the walls of said sprinkler body, an inlet into the straight duct and perforations in the upper face of the straight duct arranged in an arc substantially conforming to that of the perforations in the arc shaped duct, the axes of discharge of the perforations of both sets being wholly in advance of a perpendicular plane through the bore of the inlet.

In testimony whereof I have affixed my signature in presence of two witnesses.

LEWEN R. NELSON.
